CIGARETTE EXTINGUISHER

Joseph S. Hart, Jr., San Leandro, Calif.

Application August 16, 1946, Serial No. 691,051

8 Claims. (Cl. 131—235)

1

The present invention relates to improvements in cigarette extinguishers, and its principal object is to provide a device whereby a cigarette may be extinguished expeditiously in a few seconds and may be readily ejected thereafter.

It is further proposed to provide a cigarette extinguisher in the form of a barrel dimensioned to have a fairly close fit upon a burning cigarette inserted thereinto, and made of heat-conducting material, so as to extinguish the cigarette by heat absorption, rather than by snuffing.

It is still further proposed to mount the barrel with freedom of movement from one position to another, and to provide cigarette-ejecting means operable by such movement.

More particularly I propose to arrange the extinguisher in combination with an ash tray in such a manner that the barrel may be moved between upwardly inclined and downwardly inclined positions, the first position being the receiving position, and the ejecting means being operable to automatically eject the cigarette as the barrel approaches the downwardly inclined position.

And finally, it is contemplated to provide a unitary assembly of a plurality of barrels movable successively through upwardly inclined and downwardly inclined positions, in combination with a piston arrangement, and operating means for the latter responsive to the movement of the barrel assembly.

Further objects and advantages of my invention will appear as the specification proceeds, and the new and useful features of the invention will be fully defined in the claims hereto attached.

The preferred form of my invention is illustrated in the accompanying drawing, forming part of this application, in which:

Figure 1 shows a central vertical section through my cigarette extinguisher, as applied to an ash tray;

Figure 2, a central section through a piston assembly;

Figure 3, a front view of my extinguisher;

Figure 4, a front view of the piston assembly; and

Figures 5 and 6, detail views of cooperating parts of a snap fastener used as anchoring means for the piston assembly.

While I have shown only the preferred form of my invention, I wish to have it understood that various changes or modifications may be made within the scope of the claims hereto attached, without departing from the spirit of the invention.

2

Referring to the drawing in detail, my device comprises in its principal parts, a backing 1, adapted for fastening upon a suitable, inclined portion 2 of an ash tray 3, a bell-shaped member 4 revolvable on the backing, and having a plurality of barrels 5 projecting therefrom, a piston assembly 6, and an eccentric anchoring means 7 for the piston assembly.

The backing may be of any suitable form, and is here shown as comprising a circular concave section 8 having a flat annular flange 9, and an annular receiving lip 10, projecting at a right angle therefrom and adapted to receive the open end of the bell-shaped member 4, and to be crimped upon the latter for holding the same against endwise motion, while allowing of rotary movement.

The concave member 8 is suitably secured upon an inclined member of the ash tray by any suitable means, shown at 11.

The bell-shaped member is thus mounted with freedom of rotary movement about its own axis, and the barrels 5 are mounted in the wall of the bell-shaped member so as to project from the latter at an angle to the axis, as shown in the drawing.

The barrels 5 are dimensioned to substantially fit upon the burning end of a cigarette, and to have relatively close contact therewith, so that immediately upon insertion heat is conducted away from the cigarette, and the latter is extinguished through lack of sufficient supporting heat energy.

The outer end of each barrel may be slightly flared, as shown at 12, to facilitate insertion of the cigarette.

While any number of barrels may be selected for the purposes of the invention, I prefer to use a series of four barrels mounted equi-distant on the bell, as shown in Figure 3.

Each of the barrels has a piston 13 reciprocable therein and each piston is mounted upon the end of a connecting rod 14, the connecting rod being preferably made substantially of the thickness and material of a common pin formed with a T-head 15 adapted for anchoring in a button 16 so as to project radially with respect to the axis of the button and with freedom of pivotal movement in the axial plane of the button.

The connecting rods are preferably bent, as at 17, for alining major sections thereof with the barrels, as shown.

The button 16 may be substantially in the form of a snap fastener of conventional design, having a fixed member 18 mounted upon the backing 1,

and a movable member 19 adapted to snap upon the fixed member with freedom of revolving movement about the same.

The button is mounted upon the backing 1 in eccentric relation with respect to the axis of the bell-shaped member, preferably vertically below the latter.

My device is preferably assembled as follows:

First, the connecting rods may be pivotally secured upon the movable member 19 of the snap fastener; and the pistons may be soldered upon the projecting ends of the connecting rods to provide the assembly illustrated in Figure 2.

Next, the portion 18 of the snap fastener may be secured upon the backing in eccentric position with respect to the center of the backing; and the portion 19 may be snapped upon the portion 18 to produce the arrangement shown in Figure 4.

Thereupon the backing is applied to the bell-shaped member, care being taken that the four different pistons are guided into the four different barrels during the operation. The lip 10 is then tightened somewhat upon the rim of the bell for holding the latter in place, without interfering with freedom of revolving movement.

The assembled device may then be fastened upon any suitable support, such as the inclined portion 2 of the ash tray 3, as shown.

In use, assuming that the four barrels are in the position shown in Figures 1 and 3, it will be noted that one of the barrels points upward, while the opposing barrel points downward.

The piston in the first barrel is retracted, while the piston in the lowermost barrel is advanced to its most forward position. The user will naturally find the uppermost barrel most convenient for insertion of his burning cigarette, and the latter will be extinguished in the course of a few seconds.

A second user desiring to deposit a burning cigarette will turn the bell-shaped member through a quarter of a revolution thereby exposing a new barrel pointing upward, while the barrel previously filled moves through an angle of 90°.

A third operation will bring the first barrel to a downwardly declined position, and as the barrel approaches this position, the piston advances and ejects the cigarette.

Thus, all the cigarette inserted in the upper barrel will eventually be ejected into the ash tray from the same as it reaches the lower position.

The bell-shaped member may be operated manually as heretofore described, or any suitable means may be provided, such as a ball and ratchet arrangement of conventional form, for step-wise operation of the bell-shaped member through a quarter of a revolution, at a time.

I claim:

1. In combination, an ash tray and a cigarette extinguisher comprising a barrel assembly revolvable in the tray and having a plurality of barrels arranged angularly with respect to the axis of rotation for passing successively through upwardly inclined and downwardly inclined positions, pistons disposed in the barrels, and rotatable anchoring means for the pistons mounted below the axis of the barrel assembly to cause relative displacement between each barrel and its piston substantially along the axis of the barrel when the barrel assembly is turned.

2. In combination, an ash tray and a cigarette extinguisher comprising a barrel assembly revolvable in the tray and having a barrel arranged angularly with respect to the axis of ro-

tation for passing successively through upwardly inclined and downwardly inclined positions, a piston disposed in the barrel, and rotatable anchoring means for the piston mounted below the axis of the barrel assembly to cause relative displacement between the barrel and the pistons substantially along the axis of the barrel when the barrel assembly is turned.

3. In a cigarette extinguisher, a supporting member, means for mounting the same with freedom of rotary movement about a central axis, a barrel mounted in the member at an angle to the axis of rotation, a piston disposed in the barrel, a piston rod for the piston, and anchoring means for the piston rod mounted eccentrically with respect to the axis of rotation for causing relative displacement between the barrel and the piston substantially along the axis of the barrel when the said member is turned.

4. In a cigarette extinguisher, a supporting member, means for mounting the same with freedom of rotary movement about a central axis, a barrel mounted in the member at an angle to the axis of rotation, a piston disposed in the barrel, a piston rod for the piston, a button mounted eccentrically with respect to the axis of rotation, and means pivotally securing the free end of the piston rod to the button to cause relative displacement between the barrel and the piston substantially along the length of the barrel when the said member is turned.

5. In a cigarette extinguisher, a supporting member, means for mounting the same with freedom of rotary movement about a central axis, a series of barrels mounted symmetrically in the member in angular relation to the axis of rotation, pistons disposed in the barrels, and means operable by a turning movement of the member to cause relative displacement between each barrel and its piston substantially along the axis of the barrel.

6. In a cigarette extinguisher, a supporting member, means for mounting the same with freedom of rotary movement about a central axis, a series of barrels mounted symmetrically in the member in angular relation to the axis of rotation, pistons disposed in the barrels, connecting rods secured to the pistons, and anchoring means for the connecting rods mounted eccentrically with respect to the axis of rotation for causing relative displacement between each barrel and its piston substantially along the axis of the barrel when the said member is turned.

7. In a cigarette extinguisher, a supporting member, means for mounting the same with freedom of rotary movement about a central axis, a series of barrels mounted symmetrically in the member in angular relation to the axis of rotation, pistons disposed in the barrels, connecting rods secured to the pistons, a button revolvably mounted in eccentric relation to the axis of rotation, and means for pivotally securing the free ends of the connecting rods to the button to cause relative displacement between each barrel and its piston substantially along the axis of the barrel when the said member is turned.

8. In a cigarette extinguisher, a supporting member having a bell-shaped wall, means for mounting the same with freedom of rotation about its central axis, a series of barrels mounted symmetrically in the wall of the member in angular relation to the axis of rotation, pistons disposed in the barrels, and means within the bell-shaped member and operable by a turning movement thereof for causing relative displace-

ment between each barrel and its piston substantially along the axis of the barrel.
